UNITED STATES PATENT OFFICE.

FRANK R. BATCHELDER, OF WORCESTER, MASSACHUSETTS, ASSIGNOR TO UNIVERSAL PATENTS COMPANY, A CORPORATION OF RHODE ISLAND.

WOVEN CARRIER.

1,268,787.

Specification of Letters Patent.

Patented June 4, 1918.

Application filed December 26, 1916. Serial No. 138,720.

To all whom it may concern:

Be it known that I, FRANK R. BATCHELDER, a citizen of the United States, residing at Worcester, in the county of Worcester, State of Massachusetts, have invented a certain new and useful Improvement in Woven Carriers, of which the following is a specification, reference being had thereto in the accompanying drawings.

10 The invention has relation to carriers consisting of woven material which is formed into pockets or loops adapted to serve as receptacles. More especially it relates, though not exclusively, to ammunition carriers and in particular to those having pockets to contain individual cartridges. The principle of the invention is applicable in the case of various kinds of carriers, including those adapted to be worn as belts 15 or otherwise, but an important embodiment thereof is in a cartridge carrier or belt for use in machine-guns.

The invention, stated in general terms, consists in a carrier of the general class 20 aforesaid having a series of heavy threads or cords superficially attached in the weaving to a surface of a woven strip constituting a loop or pocket-wall, the said series making a thickening band on, for instance, 25 that portion of the pocket or loop which encircles the bullet of an inserted cartridge.

Heretofore, so far as I am aware, the thickening effect has been produced either by taking for the pocket-wall a previously-30 woven strip of somewhat greater width than the length of the desired pockets, and prior to making up the carrier or belt, doubling one marginal portion of such strip over upon the portion alongside thereof, and securing the 35 doubled-over portion in place by means of stitches or otherwise; or by increasing the number of warp-threads of ordinary character employed in weaving one marginal portion of the strip and so interweaving them 40 as to form an increased thickness of web, sometimes in the form of ribs or beads. In these latter cases, the thickening and the ribs or beads are homogeneous with the remainder of the strip, and due to the mode 45 of interweaving the warp-threads with the weft or filling, and thereby they are differentiated from the characteristic feature of the present invention, namely, the added thickening band composed of a series of 50 heavy threads or cords superficially at-

tached to one surface of a woven strip. In other words, the characteristic feature of the invention is an independent ply of heavy threads or cords, as contradistinguished from a mere increase of thickness or beaded effect due to a greater multiplicity of ordinary warp-threads and a change of weave. Although the ribs or beads of the prior art sometimes are called "cords", by reason of their appearance, they are not the same as 60 the said superficially attached heavy threads or cords of my invention.

The nature of the invention is illustrated in the drawings, in which latter,—

Figure 1 is a view on the order of a perspective showing an illustrative embodiment of the invention, namely, in a portion of the length of a woven carrier or belt, certain parts being broken away or removed in order to show features of construction more 70 clearly.

Fig. 2 is a view in vertical section through a pocket or loop.

The invention is shown embodied in a woven carrier or belt of a well-known type 80 composed of two woven strips 1, 1, placed face to face and secured together by pairs of metal binders 2, 2, etc., 3, 3, etc., at regular intervals to form pockets for containing single cartridges 4, 4, etc., the two metal 85 pieces constituting a pair of binders being located at opposite sides of the two woven strips and being fastened together, with the woven strips between them, by eyelet-rivets 5, 5, etc. This particular carrier or belt is 90 designed for use in machine-guns and accordingly, as usual, certain (2, 2, etc.) of the pairs of binders project farther from one edge of the carrier or belt than the points of the bullets of the cartridges contained 95 in the pockets, to serve to guide the carrier or belt as it is fed through a machine-gun, these pairs being known specifically as guides, and the outer extremities of the pair 2, 2, constituting a guide being secured together by an eyelet rivet 6, as shown.

At 7, 7, etc., are the heavy threads or cords lying upon surfaces of the body-webs of the respective woven strips, and constituting the thickening bands to which reference has been made. These heavy threads or cords are not embedded or incorporated in the said body-webs, but in conformity with the invention either series thereof constitutes in effect a separate ply or layer upon the body- 100 105 110

web of its respective strip. The individual heavy threads or cords of a given series lie side by side in such series, and in the weaving they are bound or tied conveniently by 5 threads of the body-web to the web-surface on which they lie, as for instance by loops 8, 8, etc., of the weft or filling of the body-web. To show one manner in which the said loops 8, 8, etc., may stand out from 10 the body-web, portions of the cords are represented at the left in Fig. 1 as having been removed. As it is not necessary that the layer of heavy threads or cords should be closely woven, the binding or tying loops 15 may be spaced somewhat widely apart, as shown.

The respective series of heavy threads or cords coöperate with the applied binders 2, 2, 3, 3, to reduce the internal dimensions and 20 capacity of those portions of the filled pockets or loops which are occupied by the bullets. Thereby is secured the desired result of causing a snug fit of the bullets within the said portions by which the latter 25 are expanded more or less, so as to obviate tendency to longitudinal edgewise curvature of the filled carrier or belt due to unequal extents of expansion adjacent opposite edges of the carrier or belt. In the filled state of 30 the pockets the main portions of the pockets are expanded somewhat more in proportion than the banded portions thereof, so that the two portions of every pocket or loop are substantially equal in external diameter. 35 Consequently, the pushers of the machine-gun act equally against the exteriors of the two portions so as to feed the carrier or belt straight forward in its passage through the gun, without tendency to skew the carrier 40 or belt edgewise by reason of unequal rates of feed at or adjoining the two edges of the carrier or belt.

The transverse width of the thickening band constituted by the series of heavy 45 threads or cords is such that the innermost of the latter coincides with the right position for the shoulder of the small or open end of the shell of a cartridge, thus providing for defining the extent of entrance of a 50 cartridge into a pocket or loop.

Preferably, though not necessarily in all cases, the heavy threads or cords are located at the exteriors of the pockets or loops, as shown in the drawings, where they are not 55 subject to injury from the sharp points of the bullets as the cartridges are being in-

serted into the pockets. If desired, they may be located upon the inner surfaces of the walls of the pockets or loops, or they may be located upon both surfaces of each 60 wall. The invention is not in all cases restricted to utilization in carriers or belts made up with the aid of metal binders. Although usually the carrier or belt will be made up of separate woven strips fastened 65 together, as in the illustrated instance, the invention is not restricted to application to a carrier or belt thus made.

What is claimed as the invention is:

1. A carrier consisting of woven material 70 which is formed into pockets or loops adapted to serve as receptacles, and having a series of heavy threads or cords superficially and exteriorly attached in the weaving upon a surface of a woven strip constituting a loop- or pocket-wall, the said series making a thickening and constricting band on a portion of the pocket or loop. 75

2. A carrier or belt consisting of woven material, which is formed into pockets or loops adapted to serve as receptacles for individual cartridges, and having a series of heavy threads or cords superficially and exteriorly attached in the weaving upon a surface of a woven strip constituting a loop- or pocket-wall, the said series making a thickening and constricting band on a portion of the pocket or loop. 80

3. A woven carrier consisting of two woven strips placed face to face and secured together at intervals to form pockets or loops constituting receptacles, the said strips as woven each having a series of heavy threads or cords superficially and exteriorly attached upon a surface thereof in the weaving, making a thickening band. 90

4. A woven carrier or belt consisting of two woven strips placed face to face and secured together at intervals to form pockets or loops adapted to serve as receptacles for individual cartridges, the said strips as woven each having a series of heavy threads or cords superficially and exteriorly attached upon a surface thereof in the weaving, making a thickening band. 100

In testimony whereof I affix my signature in presence of two witnesses.

FRANK R. BATCHELDER.
